[57] CLAIM

The ornamental design for a combined wrench and thread retracing tool, as shown and described.

DESCRIPTION

FIG. 1 is a front perspective view of a combined wrench and thread retracing tool showing a first embodiment of my new design;

FIG. 2 is a right side elevational view thereof with the left side being a mirror image thereof;

FIG. 3 is a rear perspective view thereof;

FIG. 4 is a bottom plan view thereof; and,

FIG. 5 is a right side elevational view showing a second embodiment of our new design.

FIG. 1

FIG. 2

FIG. 3

FIG. 4

FIG. 5
